UNITED STATES PATENT OFFICE.

JAMES R. HUGHES, OF SOUTH BEND, INDIANA, ASSIGNOR TO THE STUDEBAKER CORPORATION, OF SOUTH BEND, INDIANA, A CORPORATION OF NEW JERSEY.

DESIGN FOR A VEHICLE BODY COWL.

Application filed June 18, 1928. Serial No. 27,176. Term of patent 14 years.

To all whom it may concern:

Be it known that I, JAMES R. HUGHES, a citizen of the United States of America, and resident of South Bend, in the county of St. Joseph and State of Indiana, have invented a new, original, and ornamental Design for a Vehicle Body Cowl, of which the following is a specification, reference being made to the accompanying drawing, forming a part thereof.

In the drawing, the figure is a perspective view of the vehicle body cowl showing my new design.

I claim:

The ornamental design for a vehicle body cowl substantially as shown.

Signed by me at South Bend, Indiana, this 13th day of June, 1928.

JAMES R. HUGHES.
